[57] CLAIM

The ornamental design for the fishing rod holder, as shown and described.

DESCRIPTION

FIG. 1 is a perspective view of the fishing rod holder showing my new design;

FIG. 2 is a right side elevational view thereof, the left side elevational view being identical;

FIG. 3 is a front elevational view thereof;

FIG. 4 is a rear elevational view thereof;

FIG. 5 is a top plan view thereof;

FIG. 6 is a bottom plan view thereof;

FIG. 7 is a perspective view of an alternative embodiment thereof;

FIG. 8 is a front elevational view thereof, the rear elevational view being identical;

FIG. 9 is a top plan view thereof; and,

FIG. 10 is a bottom plan view thereof.
